CLAIM

The ornamental design for an electronic device with graphical user interface, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a front view of an electronic device with graphical user interface showing the claimed design; and

FIG. 2 is a front view of an electronic device with graphical user interface showing the claimed design; and,

FIG. 3 shows the design of FIG. 1 applied to an environmental electronic device.

The design of FIG. 2 may be similarly applied.

The broken lines in the figures show an electronic device having a display screen, and form no part of the claimed design.
